UNITED STATES PATENT OFFICE.

HERMAN E. S. CHAYES, OF NEW YORK, N. Y.

DENTAL DRILL.

1,267,629.

Specification of Letters Patent. Patented May 28, 1918.

Application filed August 16, 1915. Serial No. 45,743.

To all whom it may concern:

Be it known that I, HERMAN E. S. CHAYES, a citizen of the United States, residing at the borough of Manhattan, in the 5 county of New York, city and State of New York, have invented certain new and useful Improvements in Dental Drills, of which the following is a specification.

My invention relates to improvements in 10 drilling machines, particularly to those adapted to use in dentistry, such as described in my Patent No. 1,183,535 of May 16th, 1916, and in which a device is described which will drill two holes parallel 15 to each other.

The improvements contemplated and hereinafter set forth are designed to provide a simple form of device from which the drill may be easily attached and detached, and in which is maintained a moisture and dust-tight condition with respect to the working parts.

Other advantages will be apparent from 25 this description and with reference to the drawings in which: Figure 1 is a top plan view of a dental drilling machine on a large scale. Fig. 2 is a section taken in the line 2—2 of Fig. 1. Fig. 3 is a detail top plan view of the retaining plate. Fig. 4 30 is a bottom plan view of the cam disk.

Referring to Figs. 1 and 2, 8 is a toothed gear secured to the end of a flexible shaft (not shown) which transmits power from any source in a well known manner. The 35 gear 8 is mounted in one end of a frame 5 the other end of which is bifurcated as at 16—16 within the frame 5 and adjacent to the gear 8 there is mounted a vertical shaft 9 the upper end of which is journaled in 40 the frame 5 while the lower end finds a bearing in a screw plug 10 threaded into the frame 5. On the shaft 9 there is secured a toothed gear 11 which meshes with the gear 8 and a pinion 12 which meshes with 45 a gear 14 which is mounted on a vertical bolt 15 secured between the bifurcated end 16 by a nut 17.

Two arms 18—18 are also pivoted on the bolt 15 one of them having a reduced end 50 and the other a forked end 19 adapted to embrace the reduced end of the other arm. Two guard plates 20—20 are also mounted on the bolt 15, circular in shape and of slightly larger diameter than the gear 14, 55 and designed to cover the top and bottom of the gear.

The large gear 14 meshes with pinions 25 which are formed on integral hubs 24 and mounted within the ends of the arms 18. It is obvious from the description thus far 60 that when power is transmitted through the gears 8, 11, 12 and 14 to the pinions 25 that the latter will revolve at the same speed and that the arms 18 may be swung on the bolt 15 so that they can be close together as in 65 Fig. 1 or in an extreme position close up to the frame 5.

The new devices for mounting the drills in 70 position will now be described and one description will suffice for both of the arms 18—18. The end of the arm 18 is bored out on its lower side as at 36, which bore 75 communicates with a bore 34 of smaller diameter, thus forming a shoulder 35. The upper end of the hub 24 on the pinion 25 is journaled within the bore 34 while the gear 25 abuts against the shoulder 35 and is held 80 in position by a screw plug 28 threaded into the larger bore 36.

The screw plug 28 is centrally apertured 80 in line with a similar aperture in the hub 24, the latter having a feather 37 formed at the top which is adapted to engage a cut-out portion on the end of a drill 31 mounted within the hub 24 and the plug 28. 85 The drill 31 is held in position by a groove near the upper end engaging a fork 33 formed in the end of flat plate 38 having a downwardly depending reduced portion 39 which terminates in a tail 40 extending at 90 right angles therefrom.

The tail 40 lies within a recess 41 in the top of the arm 18 which contains a spring 42 coiled about the tail 40 and which presses against the depending portion 39 so that the 95 fork 33 is normally held in engagement with the groove 32 on the end of the drill 31. Thus the drill 31 is held in engagement with the feather 37 on the hub 24 and caused to revolve with the pinion 25 engaging the gear 14. Means for disengaging the drill 31 from the plate 38 are as follows:—The top surface of the arm 18 is cut away to form a depression 43 which terminates in an accurate recess 44 formed by an upwardly extending 105 flange 45 on the end of the arm 18.

Within the recess 44 there is mounted a disk 46 having an annular groove 47 and a depending cam or lug 48 formed on its under side. The cam 48 is adapted to engage the end of the plate 38 when the disk 110 is turned in either direction and it will push

the plate 38 back against the tension of the spring 42 until the fork 33 is clear of the groove 32 on the end of the drill 31 thus allowing the drill to be removed.

5 The edge of the disk 46 is slightly roughened, so that it can be turned with the thumb of the hand which holds the instrument; and this manipulation may be done no matter how close together the disks are, for instance in the Fig. 1 position.

Means for holding the disk 46 in position is provided for by a retaining plate 49 having beveled sides 50 and a semi-circular forked end 51 adapted to fit into the groove 47 in the disk 46. Slots 52 are provided and adapted to fit into the cut-out portion of the flange 45 while screws 53 serve to hold the retaining plate 49 securely in the depression 48 on the end of the arm 18. Thus all 10 the moving parts are inclosed and substantially moisture and dust-tight.

I claim:

1. In a device of the kind described, a bifurcated spring-pressed drill retaining member, and cam means for moving said member.
2. In a device of the kind described, a bifurcated spring-pressed drill retaining member, and rotatable cam means for moving said member.
3. In a device of the kind described, a bi-

furcated spring pressed drill retaining member, rotatable cam means for moving said member and a forked plate for holding the cam in operative position.

4. In a device of the character described, 35 a drill socket, a drill mounted in said socket and provided with a cut out portion, a spring pressed plate having a forked end for engagement with the cut out portion of the drill to retain the drill within the socket 46 and a cam means for moving said spring pressed plate to release the drill.

5. In a device of the character described, 45 a drill socket, a drill mounted in said socket and provided with a cut out portion, a spring pressed plate having a forked end for engagement with the cut out portion of the drill to retain the drill within the socket and a rotatable cam means for moving said spring pressed plate to release the drill, said 50 means provided with a circular groove and a retaining plate provided with a forked end for engagement within said groove to retain the cam in operative position.

In testimony whereof I affix my signature 55 in presence of two witnesses.

HERMAN E. S. CHAYES.
